VAPORIZER DEVICE

Gordon L. Brewster, Evanston, Ill.

Application April 5, 1946, Serial No. 659,775

2 Claims. (Cl. 219—45)

1

This invention relates to improvements in vaporizers and more especially to a device of that character which is adapted to be used in connection with an electric lamp bulb.

Heretofore vaporizers or disseminating devices have been of the type which substantially encase an electric light bulb thereby obscuring a material portion of the light. This type of device was further unsatisfactory in that the body portion was usually sufficiently large and heavy so as to prevent ready radiation of the heat emitted by the lamp bulb thereby causing the lamp bulb to overheat.

The heretofore used type of vaporizers usually brought the material carrying the volatile substance into direct contact with the lamp bulb thereby dissipating the substance in a short period of time and necessitating constant replacement of the volatile substance. It was to overcome these and other obvious objections that the present invention was conceived.

The main objects of this invention are to provide a vaporizer which will slowly radiate fumes from an impregnated liner contained therein; to provide a perforated metallic vaporizer having a filler of paper or other cheap absorbent material which may be impregnated with a volatile substance; to provide a vaporizer of this character which may be readily recharged when worn out; to provide a device of this character which when mounted on an electric bulb will not materially obscure the light emanating from the bulb; to provide a device of this character which will fit snugly about the stem of an electric bulb; to provide a vaporizer which will add to the ornamental appearance of an electric bulb; to provide a vaporizer having an absorbent liner which can readily be impregnated with the fluid desired to be vaporized and which, although substantially entirely exposed to the walls of the light bulb, is not in direct abutting contact therewith; to provide a device of this character whereby the heat radiated from an electric bulb will slowly vaporize the volatile material carried by the liner of the device; to provide a device of this character with which the surrounding air can be saturated with a vapor having medicinal, disinfectant or perfuming, or insecticide qualities; and to provide a vaporizer which is simple, inexpensive and easy to manufacture.

An illustrative embodiment of this invention is shown in the accompanying drawings in which:

Figure 1 is a side elevational view of my invention.

Fig. 2 is a side elevational view showing the vaporizer in cross section.

Fig. 3 is a side elevational view showing the lamp bulb in a suspended position.

Fig. 4 is a cross sectional view taken on line 3—3 of Fig. 2 but with the light bulb removed.

2

Fig. 5 is a top plan view taken on the line 5—5 of Fig. 1, but with the light bulb removed.

Referring in detail to the drawings, the outwardly flaring housing or carrier 1 is open at both ends, is preferably constructed of a rigid, light, workable, non-inflammable metallic material and generally conforming to the contour of the neck of an electric light bulb. The housing 1 is provided with an annular flange or spacer base 2, integrally secured to the lower marginal edge (as viewed in Fig. 2) of the housing 1, the free end thereof being bent upwardly to act as a circular bearing surface and define the lower opening 3. The upper end of the housing 1 is also provided with an annular flange or spacer 4 integrally secured to the inner wall below the top marginal edge of the housing and having its free end 5 bent inwardly and downwardly to define the large or upper opening 6 and act as the upper bearing surface. Perforations 6 are dispersed throughout the housing 1 and may be in a geometric or ornamental design.

An annular tube-like liner or saturator 7 comprising an outwardly flared body, preferably constructed of asbestos, cement or any other suitable non-inflammable compound, moulded, cast or shaped to conform to the shape of the neck or stem of a lamp bulb and having both ends thereof open, is designed to be encased within the housing and secured in position by the flanges 2 and 4 and their bent ends 3 and 5.

The liner 7 is impregnated with a volatile or vaporizable substance, in liquid form, at any time either before or after it is positioned within the housing by submerging it for a time in the liquid of the substance desired to be vaporized. After the liner has become fully saturated, it is removed from the fluid, the excess moisture being removed by drying or by wiping off.

The impregnated liner is encased in the housing and the housing is slid over the stem portion of a lamp bulb and the light bulb screwed into the light socket. It will be noted, especially from Fig. 2, that the bent ends or bearings 3 and 5 of the flanges 2 and 4 respectively bear directly on the lamp bulb wall and prevent the liner from coming into direct contact with the lamp bulb and at the same time prevent the vapor from the liner 7 from escaping along the side of the lamp stem.

It will be apparent from Figs. 1 to 3 that the device may be used in conjunction with a lamp bulb which is either in a suspended or upright position. When used on a lamp which is used in an upright position, the flange 2 bears directly against the marginal edges of the open end of the lamp socket. It will also be apparent that the device encloses only the stem portion of the bulb and does not, therefore, materially obscure any of the light emanating from the bulb.

When the saturated vaporizer is positioned on the lamp bulb stem and the bulb is turned on, the heat generated by the bulb will slowly volatize the substance contained in the liner and will slowly radiate and force the fumes out of the housing 1 through the perforations 6 from where they will be diffused through the surrounding air by convection.

The stem of the lamp bulb being relatively cooler than the remainder of the bulb, the fumes from the liner, positioned thereabout, will be dissipated at a much slower rate than they would be if the liner were in contact with a hotter portion of the bulb. The relatively slow dissipation of the fumes insures an even and constant distribution of the fumes over a relatively long period of time.

It is to be understood from the foregoing description that the liner may be recharged from time to time by dipping the entire device into the desired fluid or may be replaced by a new liner.

It is to be understood that numerous details of the invention herein shown and described may be altered or omitted without departing from the spirit of the invention as defined by the following claims:

I claim:

1. A vaporizer of the class described adapted to be supported by and surround the neck of an electric light bulb comprising a non-flexible housing shaped to generally conform to the contour of the neck portion of an incandescent bulb, the upper and lower ends of said housing being opened, and the outer wall being perforated, in-

wardly projecting imperforate annular flanges integrally secured to the inner wall of said housing and adjacent the upper and lower ends of said housing, the free ends of said spacer flanges being bent inwardly to form bearing members, and non-inflammable absorbent material impregnated with a vaporizable substance secured in said housing by said spacer flanges to space said material away from the walls of the incandescent lamp whereby a portion of the heat radiated from the bulb will act upon said absorbent material for disseminating the vaporizable substance.

2. The device according to claim 1 wherein the non-inflammable absorbent material is a relatively non-flexible liner preformed and of a shape generally conforming to the shape of said housing and the neck of the incandescent bulb, and wherein the inner face edges of said annular flanges snugly seat against the neck of the bulb whereby to prevent air from entering the device between the inner face edges of said flanges and the wall of the incandescent bulb.

GORDON L. BREWSTER.
